UNITED STATES PATENT OFFICE.

RUDOLF GAERTNER, OF NEW YORK, N. Y.

DESIGN FOR A PLATE OR SIMILAR ARTICLE.

50,617.

Specification for Design.

Patented Apr. 17, 1917.

Application filed February 21, 1917. Serial No. 150,276. Term of patent 3½ years.

To all whom it may concern:

Be it known that I, RUDOLF GAERTNER, a citizen of the United States, and resident of the borough of Manhattan, city, county, and State of New York, have invented a new, original, and ornamental Design for a Plate or Similar Article, of which the following is a specification, reference being had to the

accompanying drawing, forming part thereof, which drawing is a plan view of a plate or similar article, illustrating my new design.

I claim:

The ornamental design for a plate or similar article, as shown.

RUDOLF GAERTNER.
